PLAYER PIANO ROLL COMPRESSOR

Filed Nov. 8, 1926

Inventor
W. L. Patton,

By Clarence A. O'Brien
Attorney

UNITED STATES PATENT OFFICE.

WILLIAM LEE PATTON, OF AUSTIN, TEXAS.

PLAYER-PIANO-ROLL COMPRESSOR.

Application filed November 8, 1926. Serial No. 147,197.

My invention relates to improvements in devices for maintaining the music sheet of a player piano roll tightly wound on the spool provided for the purpose.

5 The purpose of the device is to provide a device in the nature of a compressor to tensionally engage opposed side portions of the music sheet roll, whereby the sheet may be wound tightly upon the spool without 10 any liability that the edge portions of the sheet will become mutilated.

The main object of the device is the provision of a compressor which may be conveniently secured to the piano structure adjacent 15 the piano roll, whereby the same is tensionally engageable against opposed sides of the roll for rewinding or paying off the music strip without any liability of damage thereto.

20 Another object resides in the simple manner of construction whereby the same can be manufactured at a very low cost.

Still another object resides in the fact that the same may be conveniently mounted 25 in the proper position in the player piano roll.

Other very novel objects and advantages will become apparent as the invention is better understood from the specification and 30 claims to follow.

In the drawing:—

Fig. 1 represents a fragmentary front elevation of a conventional player piano, showing the roll mounting with which my compressor is associated.

Fig. 2 represents a cross sectional view through the compressor and music sheet roll disclosing the manner in which my compressor is engageable with the same.

40 Fig. 3 is a vertical horizontal sectional view through the wing portion of my invention.

Fig. 4 is a perspective view of the bracket portion of my invention, and

45 Fig. 5 is a view of the elongated plate by which the wing sections of my compressor are joined.

Now for a more detail description of my invention, I refer to the drawings in which 50 like numerals designate like parts. For the convenience of illustrating my compressor in position with respect to the music sheet roll, I illustrate a fragmentary portion of a conventional player piano A. The usual 55 compartment B is provided at the front of a piano structure and in which the usual

spools C are adapted for operation. As is clearly shown in Fig. 1 of the drawings, my invention is used with the upper roll, which in the conventional player piano is the rewinding roll.

My compressor consists of a bracket plate 1, having an elongated flange at the top edge, as at 2, and a substantially shorter flange 3 at the lower edge thereof. As is clearly shown in Fig. 4, the side edges 4 of the plate converge from the end portions of the elongated flange to the width of the plate and the lower flange 3.

70 The upper flange is formed with transverse slots 5, adjacent the ends thereof. The plate 1 is formed with several openings 6 through which screws 7 may be inserted to secure the plate to the back wall of the compartment B.

75 Adapted for transverse adjustment upon the upper plate 2, I provide an elongated hinge plate 7', having an opening at each end thereof. A projecting portion of the plate 7' is rolled to provide a hinge part 8 for association with parts to be subsequently described, whereby the plates 7', 11 and 12 are hinged together.

80 The opening at each end of the elongated plate is adapted to register with the corresponding transverse slot 5 of the bracket so that the bolt 9 may be inserted through the opening and provided with a nut 10, threaded thereon for securing the members in adjusted position.

90 The compressor further consists of a pair of hinged wing plates 11 and 12 respectively, which are of substantially semi-circular shape in cross section. At the inner longitudinal edge portion of the upper plate 95 11, loop members 13 are provided substantially inwardly from the end portion thereof. The opposed longitudinal edge portions of the upper plate is curved upwardly in a manner clearly shown in Fig. 2 of the drawing.

100 The lower wing plate is provided at the ends of its inner longitudinal edge portion with a pair of loop members 14. The inner ends of the loop members 14 are adapted to engage the outer ends of the loop means of the upper wing plate, in a manner clearly shown in Fig. 3 of the drawing. The inner longitudinal edge of the lower plate is further provided with a pair of intermediate 110 loop members 15 for registry with the hinge part 8 when the two sections are in hinged

relation with the pin 16, extending through the various loops for connecting the wings together.

The outer longitudinal edge portion of the lower section is curled downwardly in a manner similar to the upwardly curved longitudinal edge of the upper section. Arranged upon the pin 16, and disposed between the opposed ends of the respective loop members 13 and 15, is a coiled spring 17. The projecting end portions of said coiled spring are adapted to engage the outer surface of the respective wing sections, whereby the sections will normally be tensionally compressed.

As is clearly shown in Fig. 2 of the drawings, the hinged wing members 11 and 12 respectively, will tightly engage opposed sides of a music sheet roll, C. After the sheet has been spent from the roll, the rewinding of same upon the upper roll with which my compressor is associated, may be done in a quick manner without any liability of the edge portions of the music sheet tearing. The outer longitudinal edge portions of the winged members are curved backwardly in a manner whereby the sheet of music may readily pass thereover, without any liability that the same will become torn.

In assembling my device in position, the plate 1 is secured to the back wall of the compartment B of the conventional player

piano. The bottom flange 3 will engage the usual shelf, while the upper flange will be located in a substantially horizontal plane 35 through the center of the roll.

To position the device in proper relation with the roll, the hinge plate 7' may be adjusted to the correct position upon the upper flange of the bracket. 40

Having thus described my invention, what I claim as new is:

1. In a compressor for player piano music rolls, a bracket plate adapted for attachment to a conventional piano structure, a 45 pair of plate members hingedly associated with said bracket plate, said plates being of arcuate cross section and tensional means associated with said plates for normally maintaining the same in compressed relation with the music roll disposed therebetween.

2. In a compressor for player piano music rolls, a bracket plate adapted for attachment to a conventional piano structure, said 55 plate being provided with a horizontally disposed flange, a hinge plate adjustable on said flange, and a pair of curved plates hingedly secured to said hinge plate, and tensional means associated with said hinge 60 connections whereby the curved plates will be normally compressed against the music roll.

WILLIAM LEE PATTON.
